UNITED STATES PATENT OFFICE

ISAAC MARINSKY, OF PROVIDENCE, RHODE ISLAND

POCKET FOR GLOVES AND THE LIKE

Application filed March 10, 1928. Serial No. 260,581.

- This invention relates to gloves of all kinds and classes including gauntlets, work gloves and the like; and the object of the invention is to provide a predetermined section or area 5 of the glove with a pocket structure into which small articles, packages, change and the like may be placed for convenient and accessible use without removing the gloves from the hand; a further object being to provide a pocket, which is formed partially from one wall of the glove; a further object being to provide means for closing the open end of the pocket tensionally or by a positive closure device; and with these and other objects 10 in view, the invention consists in a structure of the class and for the purpose specified, which is simple in construction, efficient in use, and which is constructed as hereinafter described and claimed.
- 15 The invention is fully disclosed in the following specification, of which the accompanying drawing forms a part, in which the separate parts of my improvement are designated by suitable reference characters in 20 each of the views, and in which:—
- Fig. 1 is a plan view of the palm portion of a glove showing one form of my improved pocket construction.
- Fig. 2 is a section on the line 2—2 of Fig. 1.
- 30 Fig. 3 is a section on the line 3—3 of Fig. 1.
- Fig. 4 is a view similar to Fig. 1, of only a part of the construction, and showing a modification.
- Fig. 5 is a section on the line 5—5 of Fig. 4.
- 35 Fig. 6 is a view similar to Fig. 4 but showing another modification; and,
- Fig. 7 is a section on the line 7—7 of Fig. 6.
- In the accompanying drawing, I have 40 shown a few methods of carrying my invention into effect, and in referring to a glove or gloves throughout the specification and claims, it will be understood that a hand covering body or member of any kind or class is included, and members of this kind may 45 be made from any suitable material such for example as leather, rubber, canvas and other fabrics. In the several views of the drawing, the reference character α represents the glove or a part of the glove.
- 50 In Figs. 1 to 3 inclusive, I have shown one of my improved pockets formed in the palm portion of the glove. This pocket is fashioned by cutting the palm portion of the glove transversely to form an opening 12, and securing a pocket forming member or sheet 55 13 to one side edge of the opening and to the palm portion of the glove on a line or lines of stitching as at 14, forming between the sheet 13 in the part α^2 of the palm of the glove, a pocket 15, the dimensions of which are bounded by the stitching 14 and the open end 12 of the pocket. The flap 16 of the portion α^2 formed by the opening 12 is reinforced in any desirable manner, and one member 17 of a snap fastener device is secured thereto in 60 position to engage the other member 18 of said device, the latter being secured to the pocket forming sheet 13, as clearly seen in Fig. 3 of the drawing. I also preferably include in conjunction with the member 17 and flap 16, a finger piece strap 19 which facilitates the opening of the pocket and raising of the flap to remove articles from the pocket 65 15. In Figs. 4 and 5 of the drawing, I have 70 shown a pocket formed in a glove substantially in the same manner as shown in Figs. 1 to 3 inclusive. In these figures, the reference numeral 12 a represents the open end of the pocket, 13 a the sheet secured to the glove on the line of stitchings 14 a to form the pocket 15 a . In this construction, the flap 16 a instead of being provided with the snap fastening member 17 is provided at its free edge with a reinforced portion 20, in which an elastic 80 85 or other resilient member 21 is mounted, serving to tensionally close the pocket opening at 12 a to retain articles in the pocket 15 a , eliminating the necessity of using the fastening devices, and also facilitating the expansion of the flap 16 a in inserting a finger into the pocket, as will be apparent.
- In Figs. 6 and 7 of the drawing, I have 90 shown a sheet 22, secured to the glove structure and equivalent in all respects to the sheet 95 13—13 a in the structure shown in Figs. 1 to 5 inclusive, with the exception that it does not constitute the wall of the pocket proper. In this construction, the pocket wall is formed by a member 23 secured to the inner face of 100

the portion α^2 of the glove where the pocket is located. The free end 23^a of the member 23 forms the open end portion of the pocket, which is accessible only in turning the part α^2 backwardly upon the glove structure on the line of stitching at 24, thus exposing the pocket in the part α^2 , which is of course free from the glove structure at its sides and unattached end. The latter end carries one part 25 of a snap fastener, the other part 26 being secured to the body of the glove. In other words, in this construction, the sheet 22 merely forms a closure for the opening formed in the glove by cutting the part α^2 therefrom.

15 From the foregoing, it will be apparent that the distinctive feature of my invention resides in the provision of a container or pocket integral with or constituting a unit part of a glove, and by means of which a 20 small amount of money or comparatively small articles or trinkets may be carried about in a convenient, practical and accessible manner, and especially in providing a pocket in the palm portion of the glove. With a structure of this character, it will be apparent that 25 articles may be removed from the pocket or container, without removing the glove from either hand.

While I have shown certain details of construction for carrying my invention into effect, it will be understood that I am not necessarily limited to these details, and various changes therein and modifications thereof may be made within the scope of the appended 30 claims, without departing from the spirit of my invention or sacrificing its advantages.

Having fully described my invention, what I claim as new and desire to secure by Letters Patent, is:

40 1. A glove, one part of which is fashioned to form a flap integral with the glove part along one side edge only thereof, a member secured to said glove part to close the opening formed therein by the removal of said flap, 45 and a pocket formed in the wall structure of the flap outwardly of its attached side edge and accessible when the flap is in an extended position with reference to the glove structure.

2. A glove, one part of which is fashioned 50 to form a flap integral with the glove part along one side edge thereof, a member secured to said glove part to close the opening formed therein by the removal of said flap, a pocket formed in the wall structure of 55 the flap and accessible when the flap is in an extended position with reference to the glove structure, means at the free edge of the flap for securing the same to the glove structure, and the pocket in said flap opening outwardly 60 in the direction of the attached end of the flap.

3. A glove of the class described, the palm portion of which is cut out to form a freely movable flap attached to the glove at one side 65 edge only thereof, means for closing the open-

ing formed in the palm portion of the glove in removing the flap therefrom, and a pocket formed in said flap and accessible through the inner face of the flap when the same is extended.

In testimony that I claim the foregoing as my invention I have signed my name this sixth day of March, 1928.

ISAAC MARINSKY.
